SHEET MOUNT

William C. Montignani, Jr., Upper Montclair, N. J.

Application August 12, 1943, Serial No. 498,393

5 Claims. (Cl. 129—20)

An object of the present invention is to provide such a mount preferably consisting of two parts, each preferably provided in part with an adhesive coating for ready attachment to the sheet to be mounted or to the base sheet.

Another object is to provide such a mount consisting of a first member including attaching means and a second member comprising a keeper to receive said attaching means.

Another object is to so construct the first member that it may be so folded that its attaching means will readily enter the keeper member but when permitted to resume its normal position the attaching means will be firmly and reliably interengaged with the keeper member.

Further objects and advantages of this invention will be apparent from consideration of the specification as illustrated by the accompanying drawing of an illustrative embodiment of the invention, in which drawing:

Fig. 1 is a perspective view of a book showing an inserted leaf mounted therein by means of a mount embodying the invention;

Fig. 2 is a perspective view similar to Fig. 1, but showing the inserted sheet with the first mount member attached thereto bent in such a way that the attaching hooks thereof may be entered into the loops of the keeper;

Fig. 3 is a perspective view of a preferred form of the keeper; and

Fig. 4 is a perspective view of a preferred form of the attaching member.

Referring to said drawing, the reference numeral 11 denotes a base sheet, such as a page of a printed book or album, to which a sheet is to be attached. 12 and 13 designate generally a keeper and an attaching member, respectively, made in accordance with the invention. The keeper 12 may be formed of a base layer 12a of paper, filled cloth, or other suitable material, the bottom face of which is covered with adhesive for attachment to the base sheet 11, such as the leaf of a book or album, and a top layer 12b, the latter being preferably so bent as to form loops 12c and 12d. The other parts of the top layer 12e, 12f, and 12g, are, as shown, depressed into engagement with the base layer 12a and preferably glued thereto. In this way loops are formed which are normally open to receive the attaching member 13 and which are unusually strong because they are glued to the base layer 12a at points adjacent to the loops.

The attaching member 13, as shown, consists of a longitudinally extending body portion 13a, one side of which is preferably coated with ad-

hesive material and adapted for attachment to the sheet to be mounted. Attached to the body portion 13a are two arms 13c and 13d preferably extending substantially at right angles to the body portion 13, and provided at their ends with hooks 13c' and 13d', respectively.

In the use of this improved mount, the keeper member 12 is preferably glued to the base sheet, such as the sheet 11 of a book, and the attaching member 13 is similarly glued to the edge of the sheet to be inserted, which sheet may be a piece of note paper, a photograph, clipping, or the like. As the hooks 13c' and 13d' are so located that they cannot normally be inserted into or removed from the loops 12c and 12d, the parts are so proportioned and arranged that this may be accomplished by folding the arms 13c and 13d and by folding the sheet 14 in the manner indicated in Fig. 2. In so doing, arms 13c and 13d are folded substantially at right angles to the body member 13a and the sheet 14 is folded as shown in Fig. 2, thus bringing the hooks 13c' and 13d' toward each other to a position where they may be slipped through the loops 12c and 12d. Upon permitting the sheet 14 to resume a substantially plane position, the hooks 13c' and 13d' will spread and firmly engage behind the loops 12c and 12d, respectively, thus firmly attaching the inserted sheet 14 to the base sheet 11. The sheet 14 is now preferably folded down against the sheet 11, thus providing a firmly but detachably-mounted inserted sheet which can be used, for example, for receiving notes relating to the printed material in the book. If errors are made in the notes or the notes are to be rewritten, it is a simple matter to remove the sheet 14 by reversing the process, viz., partly folding the sheet 14, as in Fig. 2, and then withdrawing the hooks from the keeper. Thus, the sheets may be readily changed while at the same time assuring that the inserted sheet is firmly held in place at all times and cannot become accidentally detached.

One form of the invention has been illustrated and described in detail for the purpose of illustration, but it will be obvious that many variations may be resorted to without departing from the spirit of the invention. For example, instead of forming the two loops 12c and 12d, a single continuous loop may be used, or a slit in the inserted sheet may receive the hooks, in which case the member 12 may be dispensed with. Furthermore, instead of having the hooks extending outwardly and away from each other they might be formed to extend inwardly toward each other. In that event, insertion of the hooks into the loops

would be accomplished by bending the sheet 14 in the opposite direction to that shown in Fig. 2.

The constructions specifically disclosed are intended merely as illustrative of the invention and not as limiting as various other modifications may be made without departing from the invention as defined by a proper interpretation of the claims which follow.

I claim:

1. A mount for detachably attaching sheets, 10 photographs, or the like to a base sheet, comprising an attaching member adapted to be attached by adhesive or the like to one of said sheets, said attaching member being formed with two substantially parallel arms having oppositely extending hook portions, and a keeper adapted for attachment to the base sheet provided with loops for receiving and retaining said hooks.
2. A mount for detachably attaching sheets, 15 photographs, or the like to a base sheet, comprising an attaching member adapted to be attached by adhesive or the like to one of said sheets, said attaching member being formed with two substantially parallel arms having oppositely extending hook portions, and a keeper adapted for attachment to the base sheet, provided with loops for receiving and retaining said hooks, said keeper being formed of a base strip and a cover strip, the cover strip being attached to said base strip at its ends and near its center, so that said loops are formed between those parts of said base strip and cover strip which are attached to each other.
3. A mount for detachably attaching sheets,

photographs, or the like to a base sheet, comprising an attaching member adapted to be attached by adhesive or the like to one of said sheets, said attaching member being formed with two substantially parallel arms having oppositely extending hook portions, and loops on said base sheet, said hook portions being adapted for attachment to the base sheet by penetrating said loops.

4. A mount for detachably attaching sheets, 20 photographs, or the like to a base sheet, comprising an attaching member adapted to be attached by adhesive or the like to one of said sheets, said attaching member being formed with two substantially parallel arms having oppositely extending hook portions, said hook portions being bent substantially at right angles to said arms, and a keeper adapted for attachment to the base sheet provided with at least one loop for receiving and retaining said hooks.

5. A mount for detachably attaching sheets, 25 photographs, or the like to a base sheet, comprising an attaching member adapted to be attached by adhesive or the like to one of said sheets, said attaching member being formed with two substantially parallel arms having oppositely extending hook portions, and a keeper adapted for attachment to the base sheet, provided with at least one loop for receiving and retaining said hooks, said keeper being formed of a base strip and a cover strip, the cover strip being attached to said base strip at its ends.
